Primary Examiner — Mary Shannon Malley*(74) Attorney, Agent, or Firm* — Wood Herron & Evans LLP(57) **CLAIM**

The ornamental design for a spa, as shown and described.

DESCRIPTION

FIG. 1 is a front right top perspective view of a spa according to the present invention.

FIG. 2 is a front view thereof.

FIG. 3 is a rear view thereof.

FIG. 4 is a left side view thereof.

FIG. 5 is a right side view thereof.

FIG. 6 is a top view thereof; and,

FIG. 7 is a bottom view thereof.

The broken lines and the masked portion outlined in broken lines illustrate portions of the spa that form no part of the claimed design.
